(57) **CLAIM**

I claim an ornamental design for the electronic open light sign housing, as shown and described.

DESCRIPTION

FIG. 1 is a perspective view of the electronic open light sign housing of the present invention;

FIG. 2 is an enlarged front elevational view of the electronic open light sign housing;

FIG. 3 is a rear elevational view of the electronic open light sign housing;

FIG. 4 is a left side end view of the electronic open light sign housing;

FIG. 5 is a right side end view of the electronic open light sign housing;

FIG. 6 is a top plan view of the electronic open light sign housing of FIG. 1; and,

FIG. 7 is a bottom view of the electronic open light sign housing.
